THEODORE F. HUSSA, OF MONTCLAIR, NEW JERSEY.

ELEMENT FOR SINGEING APPARATUS.

1,324,051.

Specification of Letters Patent.

Patented Dec. 9, 1919.

Application filed January 15, 1918. Serial No. 211,916.

To all whom it may concern:

Be it known that I, THEODORE F. HUSSA, a citizen of the United States, residing at Montclair, in the county of Essex and State 5 of New Jersey, have invented certain new and useful Improvements in Elements for Singeing Apparatus, of which the following is a specification, reference being had therein to the accompanying drawings, which form 10 a part thereof.

My invention relates to an element for singeing apparatus and more particularly to an element of this character to be used in connection with the singeing of threads embodying therein a troughed resistance member adapted to be brought to a state of incandescence by being included in an electrical circuit. Heretofore, thread singeing apparatus embodying members made incandescent by being included in an electrical circuit, have been employed, but such members have been so constructed and mounted in the apparatus, as to produce weakness in the resistance member and tend toward 15 the warping thereof when heated. Furthermore, the structure of such elements has been such as to make their mounting in series upon the bus-bars, and their adjustment thereon, in proper relation to other mechanisms in the machine, difficult.

An element of the character herein described made in accordance with my invention, is so constructed as to avoid any sharp bends in the material of which the resistance 20 member is made, the means for connecting this member with the electrical terminals incorporated in the element, being so formed as to avoid likelihood of breakage of the member adjacent said electrical terminals 25 as the result of the elongation of the member under expansion or contraction.

Another characteristic of my invention is a structure by which a vertical or lateral warping of the resistance member is prevented, the construction being such as to prevent any distortion of this member while permitting the free expansion and contraction 30 thereof under varying temperature conditions.

An element made in accordance with my invention is assembled in relation to other elements of the apparatus, means being provided whereby the element in its entirety 35 may be quickly mounted upon the bus-bars and adjusted thereon to establish the proper 40 relation between the resistance member and

those mechanisms for supporting the thread and rewinding after it has been singed.

The invention consists in the novel features of construction and combination of 45 parts hereinafter set forth and described and more particularly pointed out in the claims hereto appended.

Referring to the drawings:

Figure 1 is a side elevation of an element 50 embodying my invention;

Fig. 2 is a front view thereof;

Fig. 3 is a section on the line 3—3 of Fig. 1; and

Fig. 4 is a detail view of the resistance 55 member removed from the element.

Like letters refer to like parts throughout the several views.

In the embodiment of my invention shown in the drawings, *a* indicates the rectilineal 60 troughed portion of a resistance member adapted to be made incandescent by being included in an electrical circuit. This member is mounted upon a block *b* of insulating material, in a manner to permit it to be electrically connected with bus-bars *c* and *d* included in the structure of an ordinary singeing apparatus. The manner of mounting this member is such as to permit the free 65 expansion thereof and prevent such distortion thereof as would bring the trough out of true alinement.

At one end of the troughed portion *a*, the resistance member is turned upon a curve at substantially right angles to the troughed 70 portion thereof, to form a flexible extension *a'* adapted to be engaged between a clamp plate *e* and the flange *f* of an angular fitting, the other flange *f'* of which seats 75 upon the block *b*. At the other end of the troughed portion *a*, said member is bent upon a curve, to form an extension *a''* extending substantially at right angles to the portion *a*, the end of this extension being turned at substantially right angles, toward 80 the extension *a'*, to form a foot *a'''* adapted to be engaged between a clamp plate *g* and a plate *h* seated upon the block *b*. The clamp plate *e* and the flange *f* are recessed 85 on the edges thereof adjacent the troughed portion *a* affording clearance therefor, said recesses being of sufficient depth to permit sufficient flexure of the extension *a'*, to compensate for a slight elongation of the portion *a* at this end thereof, without developing such stresses as will distort said troughed portion *a*. The curvature of the resistance 90

member adjacent the extensions $a'-a^2$ will also tend to compensate in a measure, for this elongation. The recess in the plate e and flange f also provides a clear field for 5 the passage of the thread to the troughed portion of the member a .

The manner of mounting the extension a^2 of the member a permits the free expansion of the troughed portion of this member by 10 reason of the flexibility of said extension.

To avoid any tendency of the troughed portion a of the resistance member intermediate the extensions $a'-a^2$ to warp in any direction to an extent which would 15 materially effect the operation of the device, I provide a bridge i mounted upon the block b intermediate the plate h and the flange f' , this bridge being out of the path of the current so as to have no tendency to 20 short circuit the element. The bridge i is provided with an opening at the edge thereof through which the troughed portion a of the resistance member passes, said opening having overhung portions i' adapted to 25 engage the opposite edges of the trough while being spaced apart sufficiently to permit the insertion of the thread in the trough. Sufficient clearance is provided in the opening in the bridge i to permit expansion of the 30 member a without causing any binding thereof in the opening.

Upon the side of the block b opposite to that upon which the member a is mounted, are metallic plates j and k connected respectively by means of metallic screws, indicated in dotted lines in Fig. 1, with the flange f' and the plate h , which screws serve not only to firmly clamp said flange and said plate in position upon the block b , 40 but also as a means by which said flange and said plate and the resistance member carried thereby may be placed in electrical circuit with said bus-bars c and d included in the structure of the ordinary singeing 45 machine. Coöperating with screw threaded openings in the plate j are metallic screws j' and j^2 which are spaced apart sufficiently to span the bus-bar c , said screw having associated therewith a clamp plate j^3 adapted 50 to be forced thereby upon said bus-bar in a manner to firmly clamp said bus-bar between said plate and the plate j . Coöperating with the plate are screws k' and k^2 and a clamp plate k^3 adapted to coöperate in a 55 similar manner with the bus-bar d which is of opposite polarity to the bus-bar c . This construction not only provides a convenient manner of mechanically and electrically connecting the singeing elements 60 with the bus-bars, but permits convenient and accurate adjustment thereof in relation to other mechanisms in the machine, and insures permanency of this adjustment.

The construction above described possesses 65 the characteristics of minimizing a tendency

toward the distortion of the troughed portion a of the resistance member as a result of expansion; to prevent possibility of such distortion thereof as will vary the alinement of the trough in a manner to interfere with 70 a uniform singeing action of the flame therefrom upon the thread, and to permit the quick and convenient mounting and adjustment of the element upon the bus-bars, to insure a proper electrical engagement of this 75 element with said bars, and permanency in the adjustment of the element.

The operation of the herein described apparatus is substantially as follows:—

In singeing apparatus, a plurality of elements such as the element herein described, is mounted upon a sequence of bus-bars incorporated in the singeing apparatus, a number of said bus-bars being coupled in series. Such bars are ordinarily of short length, 85 with the ends of adjacent bars spaced apart sufficiently to permit the mounting of the singeing elements thereon.

In assembling singeing elements made in accordance with my invention in an apparatus of this character, the screws $j'-j^2$ and $k'-k^2$ are unscrewed sufficiently from the plates j and k respectively, to permit sufficient clearance between the plates $j-j^3$ or $k-k^3$ to receive the bus-bar, and thus 95 permit the element to slide freely thereupon until it has been brought into the proper relation to other mechanisms in the apparatus. When the block b has been properly positioned, the screws $j'-j^2$ and $k'-k^2$ are 100 used to clamp the bus-bars c and d between the plates $j-j^3$ and $k-k^3$ respectively, thus not only firmly securing the element in the proper relation to other mechanisms in the apparatus, but securing the proper electrical connections between the element and 105 said bus-bars.

When the circuit is closed, the current will flow from the bus-bar c through the plate j to the base f' of the angular fitting, 110 through the screws connecting said base with the plate j ; through the flange f to the extension a' ; through the troughed portion a of the resistance member to the extension a^2 thereof; through the plate h to 115 the plate k through the screws connecting said plates, completing the circuit to the other bus-bar d . As the current thus flows through the singeing element, the troughed portion a thereof will become incandescent, 120 so that a thread passing through this troughed portion, without contacting therewith however, will have the fluff thereon effectively removed.

As the temperature of the portion a rises, the material thereof will expand, the extensions $a'-a^2$ yielding under the expansion stresses sufficiently to minimize any tendency of the portion a to bulge toward or 125 away from the block b . The bridge i ar- 130

ranged about midway intermediate the extensions a' — a^2 will prevent any lateral bulging or distortion of the portion a without interfering with the expansion of said portion because of the clearance afforded in the opening in said bridge about said troughed portion. The bottom of the opening in the bridge i will prevent bulging toward the block b , while the overhung portion i' will positively prevent bulging away from said block.

The bridge i must be so constructed as not to interfere with the expansion of the portion a between it and either extensions a' or a^2 thus avoiding any tendency of the troughed portion to warp between said bridge and said extensions respectively.

The curvature of the resistance element at the point of connection between the portion a and the extensions a' and a^2 respectively avoids any weakness in the resistance element at this point, and compensates for the expansion of the troughed portion, minimizing the flexure of the extensions a' — a^2 .

25 The manner of mounting the bridge i prevents short circuiting of the element through this bridge.

It is not my intention to limit the invention to the precise details of construction shown in the accompanying drawings, it being apparent that such may be varied without departing from the spirit and scope of the invention.

Having described the invention what I claim as new and desire to have protected by Letters Patent is:—

1. An element for singeing apparatus embodying therein a troughed resistance member having resilient extensions at the opposite ends thereof, projecting from the bottom of the trough of said member and at substantially right angles thereto, a support of insulating material for said member, clamps of electro-conductive material adapted to operatively engage said extensions respectively, and means whereby said clamps may be electrically connected with a source of electrical supply.

2. An element for singeing apparatus embodying therein a troughed resistance member having resilient extensions at the opposite ends thereof, one of said extensions having an inturned end extending at substantially right angles thereto, a support of insulating material, an angular fitting carried thereby, a clamp plate, whereby one of said extensions is secured in relation to said support, said fitting and its coöperating clamp plate having recesses therein providing clearance for the troughed portion of said resistance member, a plate seated upon said support, a clamp plate coöperating therewith whereby the inturned edge of the other extension is secured to said support, and means whereby said fitting and said plate

may be electrically connected with a source of electrical supply.

3. An element for singeing apparatus embodying therein a troughed resistance member having resilient extensions at opposite ends thereof, projecting from the bottom of the trough of said member and at substantially right angles thereto, a support of insulating material for said member, clamps of electro-conductive material adapted to operatively engage said extensions respectively, means carried by said plate intermediate the extensions on said resistance member whereby warping of said troughed portion in any direction is prevented, and means whereby said clamps may be electrically connected with a source of electrical supply.

4. An element for singeing apparatus embodying therein a troughed resistance member having resilient extensions at the opposite ends thereof, projecting at substantially right angles thereto, a support of insulating material for said member, clamps of electro-conductive material adapted to operatively engage said extensions respectively, a bridge carried by said support and insulated thereby from said resistance member, having an opening through which said resistance member passes, overhung portions on said bridge adapted to engage the edge of the troughed portion of said resistance member, and means whereby said clamps may be electrically connected with a source of electrical supply.

5. An element for singeing apparatus embodying therein a troughed resistance member having resilient extensions at the opposite ends thereof projecting at substantially right angles thereto, a support of insulating material for said member, clamps of electro-conductive material adapted to operatively engage said extensions respectively, electro-conductive plates carried by said support, mechanically and electrically connected with said clamps respectively, two screws carried by each of said plates and adapted to span the bus-bars, and a clamp plate mounted upon said screws whereby said electrical resistance member may be supported from, electrically connected with and adjustably mounted on a bus-bar.

6. An element for singeing apparatus embodying therein a block of insulating material, an angular fitting adjacent one end thereof and a plate adjacent the other end thereof, said fitting and said plate being of electro-conductive material, plates mounted upon the other side of said block, mechanically and electrically connected with said fitting and said first named plate respectively, two screws carried by each of said last named plates spaced apart thereon sufficiently to span a bus-bar, clamp plates mounted upon said screws respectively

whereby said block may be supported from and adjustably mounted upon a bus-bar, and said fitting and said first named plate may be electrically connected therewith, a troughed resistance member having resilient extensions at the opposite ends thereof projecting at substantially right angles to said resistance member, one of said extensions having an inturned end, a clamp plate co-operating with said fitting and with an extension at one end of said resistance member, said fitting and the clamp plate co-operating therewith having recesses therein providing clearance for the troughed portion of 15 said resistance member, a second clamp plate

adapted to coöperate with said first named plate in securing the inturned end of said other extension, and a bridge carried by said block having an opening through which said resistance member passes, and overhung portions thereon adapted to engage the edge of the troughed portion of said resistance member. 20

In witness whereof, I hereunto affix my signature, in the presence of two subscribing 25 witnesses, this 19th day of December 1917.

THEODORE F. HUSSA.
